ROTARY SPOON BAITS

Maurice Bousquet, Paris, France

Application February 16, 1954, Serial No. 410,567

Claims priority, application France June 11, 1953

2 Claims. (Cl. 43—42.19)

The present invention relates to rotary spoon baits of the type having a blade carried by a U-shaped yoke piece the two legs of which are traversed by the spindle of the spoon, one end of said spindle being formed into a loop adapted to receive a leader.

One object of the invention is to provide a rotary spoon of the character above described the attractive effect of which is increased as compared with that of the spoons heretofore obtainable.

Another object of the invention is to provide a rotary spoon of the character above described wherein provision is made for balancing the weight of the blade.

In order to attain this object as well as others, one leg of the yoke piece is formed with an extension stretching out from the spindle loop in the vicinity of the spoon spindle.

On a preferred embodiment of the invention said extension of the yoke piece extends in a direction substantially parallel with the spoon spindle.

In order to achieve a material balancing of the weight of the blade the extension of the yoke piece has a width definitely greater than the width of the yoke piece.

According to another feature of the invention, the face of the extension of the yoke piece remote from the blade has reflecting and/or absorbing properties for the incident light falling upon said face of the yoke piece, whereby the attractive character of the lure is increased during operation either by an increase or a decrease of the reflecting power of the spoon, or by creating a contrasting effect with respect to the blade.

Still another object of the invention is to provide a rotary spoon of the character above described in which any risk of jamming of the yoke piece on the spindle and subsequently of the blade or of distortion of the assembly is positively eliminated. With this latter object in view the end portion of said extension of the yoke piece is bent toward the spindle of the spoon so as to form a third leg also traversed by the spindle.

The invention may be more clearly understood by reference to the accompanying drawings in which:

Fig. 1 is an elevational view of a preferred embodiment of the invention provided with a yoke piece formed into an additional leg,

Fig. 2 is a corresponding side view,

Fig. 3 is an elevational view of an embodiment similar to that represented in Fig. 1 but having no lead weight,

Fig. 4 is an elevational view similar to Fig. 3, of a modification also having a yoke piece formed into an additional leg,

and Figs. 5, 5a; 6, 6a and 7, 7a show in elevation and top views respectively, three different embodiments of yoke pieces.

In the embodiment shown in Figs. 1 and 2, the blade 1 of the spoon bait is threaded in the usual manner over a yoke piece 2 traversed by the spindle 13 of the spoon. The spindle 13, in the present embodiment carries the hook 3. According to the invention the lower leg of the yoke piece is formed into an extension 4, which may

2

be oriented in a direction substantially parallel with the spindle 13 as shown in the drawing.

Between the lower leg of the yoke piece 2 and the lower end of the spindle 13 are arranged two lead weights 6 and 7 (which may be possibly replaced by a single lead weight), two balls 8, 9 and if desired an intermediate ball 11.

The lead weight or weights may, if desired, be fixedly secured to the spindle as by means of crushing.

10 The edges of the extension 4 of the yoke piece 2 may be parallel with each other, the width of this extension being substantially equal to the width of the yoke piece proper 2. Said extension 4 may also have any other suitable shape such as that of a fish.

15 It will be readily appreciated that the weight of the blade 1 may be at least partially balanced by the weight of the extension 4, thus improving the operation of the spoon to a large extent.

The extension 4 may be bright all over its area or possibly have zones of various reflecting powers, for instance by application of paint or lack, possibly resulting into marblings, mottlings, or the like thus increasing the attractive effect of the lure in operation.

In Figs. 1 to 3 the extension section 4 forms a continuation of the yoke piece section 2 and has its end portion bent at right angles as at 5. In other words this bent portion 5 forms a third leg of the double U-shaped yoke means 2, 4 also perforated and traversed by the spindle 13. This arrangement eliminates the possibility for the double U-shaped yoke means 2, 4 to get jammed and/or distorted, thus insuring a reliable operation.

Fig. 3 illustrates an embodiment similar to that of Fig. 1 but in which the lead weights 6 and 7 have a number of balls 12 substituted therefor.

35 Fig. 4 also illustrates an embodiment similar to that of Fig. 1, but having no lead weight on the spindle and the ball 8 on which bears the yoke piece is secured to the spindle in the same manner as in the embodiment shown in Fig. 1.

40 Figs. 5 and 5a illustrate the yoke piece used in the embodiment of Figs. 1 and 2, wherein the extension 4a has the same width as the yoke piece proper 2.

Figs. 6 and 6a illustrate a modification of a yoke piece in which the extension 4a is wider than the yoke piece 2 and Figs. 7 and 7a a modification in which the two edges of the extension 4b are diverging downwardly.

45 Any of these modifications could be used in the lures according to the invention.

Various changes and modifications may be made without departing from the spirit and scope of the present invention and it is intended that such obvious changes and modifications be embraced by the annexed claims.

Having thus described the invention, what is claimed as new and desired to be secured by Letters Patent, is:

55 1. A rotary spoon for use in fishing; comprising an elongated spindle provided with a loop at one of its ends for receiving a leader and with hook means at its other end, one U-shaped yoke section having first and second spaced apart legs and an arcuate portion interconnecting

60 said legs, said legs being provided, respectively, with aligned perforations, said spindle extending through said perforations and supporting said one U-shaped yoke section adjacent said one end of said spindle with said first leg located adjacent said loop, a blade member loosely engaged by said arcuate portion and positioned at the same side of the spindle at which said one U-shaped yoke section extends, another U-shaped yoke section forming a continuation of said one section and directed lengthwise of and at a side of said spindle opposite to that of

65 said one U-shaped yoke section, said other section being provided with a third leg bent back and perforated for passage of said spindle therethrough, the length of said

other section being considerably greater than the distance between the legs of said one section and the combined length of said one section and said other section corresponding approximately to the entire spindle length located between said loop and said hook means.

2. A rotary spoon for use in fishing; comprising an elongated spindle provided with a loop at one of its ends for receiving a leader and with hook means at its other end, one U-shaped yoke section having first and second spaced apart legs and an arcuate portion interconnecting said legs, said legs being provided, respectively, with aligned perforations, said spindle extending through said perforations and supporting said one U-shaped yoke section adjacent said one end of said spindle with said first leg located adjacent said loop, a blade member loosely suspended from said arcuate portion and swingable relative to the spindle, and another U-shaped yoke section forming a continuation of said one section and being positioned with the major portion of said other section spaced from said spindle, said other section being provided with a third leg bent toward said spindle and per-

forated for passage of the latter therethrough, the distance between said third leg of said other section and the second leg of said one section being considerably greater than the distance between said second and said first legs of said one section and the combined length of said one section and said other section corresponding approximately to the entire spindle length located between said loop and said hook means, said one U-shaped yoke section being directed in opposed relation to said other U-shaped yoke section, both said sections forming together double U-shaped yoke means.
